UNITED STATES PATENT OFFICE.

ARNOLD STUCKI, OF ALLEGHENY, PENNSYLVANIA.

DRAFT-GEAR FOR RAILWAY-CARS.

SPECIFICATION forming part of Letters Patent No. 727,485, dated May 5, 1903.

Application filed December 23, 1902. Serial No. 136,374. (No model.)

To all whom it may concern:

Be it known that I, ARNOLD STUCKI, a citizen of the United States, and a resident of Allegheny, Pennsylvania, have invented certain Improvements in Draft-Gear for Railway-Cars, of which the following is a specification.

One object of my invention is to construct a simple and compact form of draft-gear for railway-cars; and a further object is to permit lateral swinging movement of the draft-bar under control of the springs. These objects I attain in the manner hereinafter set forth, reference being had to the accompanying drawings, in which—

Figure 1 is a view, partly in plan or top view and partly in section, of draft-gear for railway-cars in accordance with my invention. Fig. 2 is a view, partly in side elevation and partly in longitudinal section, on the line *a a*, Fig. 1. Fig. 3 is a sectional plan view of one of the elements of the gear. Fig. 4 is a top view of the same, and Fig. 5 is a front view.

11 represent the center sills of the car, and 2 the draft-bar which carries the coupling-head. To the opposite sills 1 are secured bearing plates or brackets 3 and 4, which may be independent of each other, if desired, or 30 may be united to form a double bracket, if preferred, the brackets 3 serving as stops to limit the forward movement of the forward follower 5, and the brackets 4 in like manner serving to limit the rearward movement of 35 the rear follower 6. Against the front face of the forward follower 5 bears the rear end of the draft-bar 2, and against the back face of the rear follower 6 bears a block 7, which is secured to the usual yoke 8 with which the 40 draft-bar is provided.

Between the front and rear followers 5 and 6 are confined any desired number of spring structures, two of which are shown in the present instance, each of these spring structures consisting of a two-part casing composed of members free to slide laterally past each other, and confined between them is a transverse spring element of any desired character.

50 In the present instance each spring element comprises an outer spring-coil 9 and an

inner spring-coil 10, lighter than the outer coil, and each member of the spring-casing comprises a face-plate 11, diagonal side plates 12, and an end plate 13, said end plate constituting one of the end bearings for the 55 spring-coils and the diagonal side plates of the two members having edge bearing upon each other.

A portion of each edge of each of the diagonal side plates 12 presents a beveled rib 14, and the remaining portion presents a beveled groove 15, and between the rib and groove is a shoulder 16. When the two members of the casing are fitted together, the ribs 60 of the side plates of one member fit into the grooves of the side plates of the other member and there is a space between the shoulders 16, as shown in dotted lines in Fig. 1. When, however, the face-plates of the two 70 members of the spring-casing are pressed toward each other, the wedge-like action of the side plates causes lateral sliding movement of each member in respect to the other and consequent compression of the interposed 75 springs. The movement is therefore resisted, not only by the resiliency of the springs, but also by the frictional contact with each other of the side plates of the casing, which frictional surface is increased by reason of the 80 beveling of the edges of these side plates.

Undue compression of the springs is prevented by contact of the shoulders 16 of the side plates, which limits the extent of lateral sliding movement of the members of the 85 spring-casing.

When there is buffing strain upon the draft-bar, the forward follower will be pushed rearwardly, the rear follower seating against the rear brackets 4, and when there is draft 90 strain upon the bar the rear follower 6 will be drawn forwardly, the forward follower seating against the forward brackets 3, and either movement will be attended by a laterally-sliding movement of the members of 95 the spring-casings and consequent compression of the springs.

The bearing-faces of the forward follower 5 and the rear end of the draft-bar 2 and of the rear follower 6 and filling-block 7 have a 100 wedge formation consisting of two or more symmetrically-inclined surfaces forming suit-

able projections or depressions in the follower-plates and corresponding depressions or projections in the draft-bar and yoke, so that when the draft-bar is swung to one side 5 or the other the followers will be compressed and will cause corresponding compression of the springs. Hence while this construction tends to maintain the draft-bar normally in its central position it permits lateral movement of the draft-bar in either direction 10 when the cars are rounding curves and insures the return of the draft-bar to the central position when, after having been deflected to right or left, it is released and permitted to so return. By reason of this freedom of lateral movement of the draft-bar I prevent the strains upon the end of the car 15 and upon the couplers, sills, and other parts of the equipment which result when cars with rigidly-mounted draft-bars are passing curves, and this result is attained without resorting to any complicated construction of draft-gear and consequent expense.

Vertical displacement of the draft-gear is 20 prevented by means of a bottom plate 17 and a top plate 18, these plates spanning the space between the sills 1 and being suitably secured at their ends to said sills.

When the spring-casings are subjected to 25 pressure, the face-plate of one member of the casing moves forwardly and the face-plate of the other member moves rearwardly, and the interposed springs are therefore not only compressed, but also caused to assume an 30 inclined position, and in order that the springs may not be distorted or forced from their places because of this change of position each of the end plates 13 of each spring-casing provides a rounded bearing, which permits 35 rocking movement of the spring. Thus, as shown in Fig. 1, the end plates of the casing of the forward set of springs have rounded portions 13^a, upon which are seated rocking plates or saddles 13^b, upon which the 40 ends of the springs have their bearing, while the rear set of springs bear directly upon the end plates 13, which are rounded throughout.

Having thus described my invention, I claim and desire to secure by Letters Patent—

1. A spring structure for the draft-gear of railway-cars, said structure having two members with diagonal side plates bearing upon each other, and end plates providing bearings 55 for the interposed spring element, substantially as specified.

2. A spring structure for the draft-gear of railway-cars, said structure having two members with diagonal side plates having interlocking bearing upon each other, and end plates providing bearings for the interposed spring element, substantially as specified.

3. The combination in draft-gear for railway-cars, of the draft-bar, a follower acted 60 upon thereby, and one or more spring structures acted upon by said follower and each

comprising two members with diagonal side plates bearing upon each other, and end plates providing bearings for the interposed spring element, substantially as specified. 70

4. The combination in draft-gear for railway-cars, of the draft-bar, a follower acted upon thereby, and one or more spring structures acted upon by said follower and each comprising two members with diagonal side 75 plates having interlocking bearing upon each other, and end plates providing bearings for the interposed spring element, substantially as specified.

5. The combination in draft-gear for railway-cars, of the draft-bar, its yoke, front and rear followers, stops therefor, and one or more interposed spring structures each comprising two members with diagonal side plates bearing upon each other and end plates providing 85 bearings for the interposed spring element, substantially as specified.

6. The combination in draft-gear for railway-cars, of the draft-bar and its yoke, front and rear followers, stops therefor, and one or more interposed spring structures each comprising members having diagonal side plates with interlocking bearing upon each other, and end plates providing bearings for the interposed spring element, substantially as specified. 90

7. The combination in draft-gear for railway-cars, of the draft-bar, a follower acted upon thereby, and one or more spring structures acted upon by said follower and each comprising two members with diagonal side plates bearing upon each other, and end plates providing bearings for the interposed spring element, each of said side plates having one edge partly ribbed and partly recessed, with 100 intervening shoulder, the ribbed portion of the edge of one side plate engaging the recessed portion of the edge of the opposed side plate, substantially as specified.

8. The combination in draft-gear for railway-cars, of the draft-bar and its yoke, front and rear followers, stops therefor, and one or more interposed spring structures each comprising members having diagonal side plates bearing upon each other, and end plates 115 between which the spring element is interposed each of said side plates having an edge partly ribbed and partly recessed with intervening shoulder, the ribbed portion of the edge of one side plate engaging the recessed 120 portion of the edge of the opposed side plate, substantially as specified.

9. A spring structure for the draft-gear of railway-cars, said structure having two members with diagonal side plates bearing upon each other, and end plates providing rounded 125 bearings for the interposed spring element, substantially as specified.

10. A spring structure for the draft-gear of railway-cars, said structure having two members with diagonal side plates having interlocking bearing upon each other, and end 130

plates providing rounded bearings for the interposed spring element, substantially as specified.

11. A spring structure for the draft-gear of railway-cars, said structure having two members with diagonal side plates bearing upon each other, end plates with rounded bearings, saddles mounted so as to rock on said bearings, and an interposed spring structure bearing upon said saddles, substantially as specified.

12. A spring structure for the draft-gear of railway-cars, said structure having two members with diagonal side plates having interlocking bearing upon each other, end plates with rounded bearings, saddles mounted so as to rock on said bearings, and an interposed spring structure bearing upon said saddles, substantially as specified.

13. The combination in draft-gear for railway-cars, of the draft-bar, a spring structure, and an interposed follower having a wedge bearing upon the draft-bar, whereby lateral movement of said draft-bar will effect compression of the spring structure, substantially as specified.

14. The combination in draft-gear for railway-cars, of a draft-bar, a spring structure, and an interposed follower movable longitudinally with the draft-bar to compress the spring structure, said follower also having a wedge bearing upon the draft-bar whereby lateral movement of the latter will also effect

compression of the spring structure, substantially as specified.

15. The combination in draft-gear for railway-cars, of the draft-bar and its yoke, front and rear followers, one movable rearwardly and the other movable forwardly with the draft-bar, stops for preventing other movement of said followers, and a spring structure interposed between the followers and compressed by movement of either follower, each follower having a wedge bearing upon the draft-bar, whereby lateral swinging of said bar also causes longitudinal movement of the followers, substantially as specified.

16. The combination in draft-gear for railway-cars, of the draft-bar and its yoke, front and rear followers, a block interposed between the yoke and the rear follower, a spring structure interposed between the followers, and stops for restricting the forward movement of the forward follower and the rearward movement of the rear follower, each follower having a wedge bearing upon that member of the draft-bar with which it engages, substantially as specified.

In testimony whereof I have signed my name to this specification in the presence of two subscribing witnesses.
